CLAIM

I claim the ornamental design for a vanity with wraparound drawer fronts, as shown and described.

DESCRIPTION

FIG. 1 is a front perspective view of a vanity with wrap-around drawer fronts.

FIG. 2 is a front view thereof.

FIG. 3 is a right side view thereof, the left side view being a mirror image thereof; and,

FIG. 4 is a top view thereof.

The broken lines shown in the drawing are for illustrative purposes only and form no part of the claimed design.
